US0D1002304S

(12) **United States Design Patent** (10) **Patent No.:** **US D1,002,304 S**
Chen (45) **Date of Patent:** **** Oct. 24, 2023**

(54) **FLOWER CLIPPERS**

(71) Applicant: **RHINOCEROS MANUFACTURING (ZHONGSHAN) LTD**, Guangdong (CN)

(72) Inventor: **Renfu Chen**, Guangdong (CN)

(73) Assignee: **RHINOCEROS MANUFACTURING (ZHONGSHAN) LTD**, Zhongshan (CN)

(**) Term: **15 Years**

(21) Appl. No.: **29/779,148**

(22) Filed: **Apr. 16, 2021**

(30) **Foreign Application Priority Data**

Oct. 27, 2020 (CN) 202030640377.X

(51) **LOC (14) Cl.** **08-03**

(52) **U.S. Cl.**

USPC **D8/5; D8/57**

(58) **Field of Classification Search**

USPC D8/5, 57, 58

CPC B26B 13/20; B26B 13/06; B26B 13/12;

A01G 3/02

See application file for complete search history.

Primary Examiner — Rachel A. Voorhies

Assistant Examiner — Benjamin D. Wannemacher

(57) **CLAIM**

The ornamental design for flower clippers, as shown and described.

DESCRIPTION

FIG. 1 is a perspective view of flower clippers showing our new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

1 Claim, 7 Drawing Sheets
